By

Inventor,

William H. Barten.

UNITED STATES PATENT OFFICE.

WILLIAM H. BARTEN, OF ALLEN, SOUTH DAKOTA.

INK-WELL CASE.

SPECIFICATION forming part of Letters Patent No. 634,795, dated October 10, 1899.

Application filed June 20, 1899. Serial No. 721,272. (No model.)

To all whom it may concern:

Be it known that I, WILLIAM H. BARTEN, a citizen of the United States, residing at Allen, in the county of Washabaugh, State of 5 South Dakota, have invented certain new and useful Improvements in Ink-Well Cases; and I do hereby declare the following to be a full, clear, and exact description of the invention, such as will enable others skilled in the art to 10 to which it appertains to make and use the same.

My invention relates to cases for ink-wells, and has for its object to provide a cheap and simple case to receive and hold the glass ink-receptacle used upon school-desks in connection 15 with a metallic frame.

As is well known, the school-desk ink-well consists of a cylindrical glass vessel having an annular flange at its top. This ink vessel or receptacle fits into a metallic frame provided with a lid and which is secured upon a desk in such a position that the glass portion will project into the desk through a perforation formed in the top thereof. Through carelessness in leaving the lids of the wells open 25 when not in use much ink is wasted by evaporation, it becomes thickened and must be replenished, and, moreover, is a constant source of temptation to the mischievous. With my invention after the using of ink is finished 30 for the day the glass receptacles are raised from their frames in the desks and are placed in the case. This case is formed adjustable, so as to be made to receive the ink-receptacles of uniform size, whatever such size may 35 be, within certain limits. A cover is formed for the case having variable connections with the case to fit upon the whole group of receptacles and close them against evaporation, dirt, &c. Within the case is also a receptacle 40 for penholders having a pad at the bottom to receive an antiseptic solution to eradicate any disease-germs that may have adhered to the penholders from diseased pupils or from any other source.

45 In the drawings forming a portion of this specification and in which like letters of reference indicate similar parts in the several views, Figure 1 is a perspective view of a case with the lid detached therefrom. Fig. 2 is a 50 front end view of my case closed. Fig. 3 is a rear end view of my case with lid closed.

Fig. 4 is a detail section of an ink-receptacle and the supporting-plates.

Referring now to the drawings, in operating in accordance with my invention I form 55 a case comprising a base *a*, sides *b* and *c*, and rear *e*. A partition *f* is placed within the case and adjacent the front end thereof resulting in the formation of a narrow compartment *g* and a broader compartment *h*, the 60 former having at its bottom one or more layers of absorptive material *i* to receive an antiseptic solution, as hereinbefore mentioned. The inner face of the end *d* is recessed, as shown at *k*, and diametrically opposite the 65 recess *k* is a second recess *l*, as shown, enabling the more ready removal of penholders from the compartment.

Upon the base *a* and within the major compartment *h* I arrange a pad *m*, of felt or other 70 suitable material, to receive direct pressure of the bases of the ink-receptacles.

Covering the compartment *h* is a fixed plate *n* of suitable metal having square holes *o* therein. The plate *n* has additional holes 75 through which are passed screws *p*, having washers *r* thereon. Upon the plate *n* is placed a second plate *s*, which lies beneath the washers *r*, said plate having slots *t* therein for the passage of the screws *p*, whereby the 80 plate *s* may be adjusted laterally with respect to plate *n*, the plate *s* being held in its adjusted position by means of the screws *p* when they are tightened. Plate *s* has square holes *u* therein corresponding to holes *o* in 85 plate *n*, the diagonals of the holes being disposed in the line of adjustment of plate *s*, whereby when said plate is adjusted the lining holes in the two plates may coact to form square holes of different diameters. 90

For the case I form a lid or cover *v*, having a padded under side covered with a waterproof material, and which cover is held in plate upon the case through the medium of pins *w* at the rear edge thereof, which are 95 adapted to enter perforations in upwardly-projecting straps *x*, secured to the rear face of the case. There are a number of these perforations, so that the cover may be adjusted as may be required at different distances from the upper face of plate *s*. 100

Secured to the front edge of the cover *v* is

a plate *y*, which extends at right angles to the said edge, and has a series of vertically-alined perforations *a'*. Secured to the front face of the case and coöperating with plate *y* is a second plate *b'*, having a vertical slot *c'*, through which plate *y* projects when the cover is in place. Extending outwardly from plate *b'* and in a position to lie parallel with plate *y* is a flange *d'*, having vertically-alined 10 perforations corresponding with those in the plate *y*. Fastened rigidly to the plate *b'* is a spring-wire whose lower portion lies against the plate, after which it is bent outwardly and then inwardly and then is brought to lie 15 against plate *b'* in the plane of the lower portion, from which position it is bent laterally at right angles to form a straight portion adapted to enter alining perforations in plates *y* and *b'*.

20 The wire *e'* is preferably secured in place through the medium of a loop at its lower end, through which a screw *f'* is passed into the case for holding plate *b'* in position. As shown, a plurality of screw-holes *g'* are formed 25 in plate *b'* to allow manipulation of the wire catch to engage different alining perforations. It will be noted that the wire catch is substantially L-shaped, with a loop at its lower end and with an outward bend in its stem.

30 In practice the plates *n* and *s* are adjusted to cause their coöperating square openings to fit snugly an ink-well, after which the wells are placed in the several openings, it being readily understood that the case may be built 35 to accommodate any number of wells. The cover is then adjusted by inserting its pins in the proper perforations of the back straps, after which it is pressed down upon the tops of the wells to bring the plate *y* adjacent 40 flange *d'*, when the wire catch may be readily manipulated to enter alining perforations in the plate and flange to hold the cover tightly upon the wells. It is readily understood that the wells are each provided with an annular 45 flange at their upper edges which prevent them being forced through the openings in the supporting-plates *n* and *s*, while the pad within the case offers a yieldable support for them.

50 One of the attaching-screws *p* is passed through a plurality of layers of felt, kid, or other suitable material, forming a pen-wiper.

Thus it will be seen that with my apparatus the wells may be easily collected and at 55 the same time the pens collected and that after the latter have been cleaned upon the wiper they may be deposited in the receptacle therefor. In practice a scholar's well is first lifted from the desk and placed in the case. 60 Then his pen is wiped and then placed in the receptacle therefor, the same being repeated at the desk of the next scholar.

It will be readily understood that I may vary the specific construction and arrangement herein shown and described, that I may 65

use whatever material in its manufacture that may appear advisable, and that I may vary the proportions at will without departing in any manner from the spirit of my invention.

Having thus described my invention, what I claim is—

1. The combination with a receptacle of a plate fixed thereto and having angular openings therein, and a second plate having also similar angular openings and adjustable over 75 the first plate, the openings of one plate being arranged to aline with those of the other plate, and means for holding the plates upon the receptacle.

2. The combination with a receptacle of a 80 plate fixed thereto and having square openings therein, a second plate having also square openings and adjustable over the first plate, said openings of one plate being arranged to aline with those of the other plate and disposed with their diagonals in the line of adjustment of the adjustable plate.

3. The combination with a receptacle of a plate fixed thereto and having square openings therein, a second plate having also square 90 openings therein, the openings of one plate being adapted to aline with the corresponding openings of the other plate, the second plate being adapted for adjustment over the first plate, a yieldable pad beneath the plates, and a cover adjustable vertically with respect to the plates.

4. The combination with a receptacle of a plate fixed thereto and having square openings therein, a second plate having also square 100 openings therein adapted to aline with the corresponding openings of the first plate, said second plate being adjustable over the first plate, perforated straps secured to the receptacle, a cover having pins adapted to enter certain of said perforations, a perforated plate carried by the cover, a corresponding perforated plate carried by the receptacle, and a latch adapted to enter alining perforations 105 in the last-named plates.

5. The combination with a receptacle divided into compartments, of a plate fixed and covering one of the compartments and having angular openings therein, a second plate adjustable over the first plate and having angular 115 openings adapted to register with the first-named openings, the openings in the plates being disposed with their diagonals in line with the adjustment of the plate, a pad beneath the openings, a padded cover having adjustable connection with the receptacle, and an absorptive pad within the second compartment.

In testimony whereof I affix my signature in presence of two witnesses.

WILLIAM H. BARTEN.
